UNITED STATES PATENT OFFICE.

CHARLES S. YOUNG, OF LOS ANGELES, CALIFORNIA.

BLOTTING PAD.

Application filed May 16, 1922. Serial No. 561,373.

To all whom it may concern:

Be it known that I, CHARLES S. YOUNG, a citizen of the United States, residing at Los Angeles, in the county of Los Angeles and State of California, have invented a new and useful Blotting Pad, of which the following is a specification.

This invention relates to blotting pads of the character employing a blotting element, a holder therefor and a resilient member between the holder and the blotting element, and an object of the invention is to provide a novel construction of blotting pad wherein the blotting element is securely held in place in the holder by the expansive force of the resilient member, thus making a very simple device.

Another object of the invention is to provide a blotting pad which may be applied to a surface simply by pressing it thereon; it being understood that other blotting pads must be rocked over the surface to be blotted.

Still another object of the invention is to provide a blotting pad which may be constructed entirely of sheet material; it being apparent hereinafter that in addition to a simple sheet metal box-like holder, all I require to carry out my invention is a blank of sheet rubber or like material, a smaller blank of less compressible material, such as cardboard, and a sheet of blotting paper.

The accompanying drawings illustrate the invention:

Figure 1 is a perspective view of a blotting pad constructed in accordance with the provisions of this invention.

Fig. 2 is a longitudinal mid-section of the pad.

Fig. 3 is a transverse mid-section of the pad.

There is provided a suitable holder, preferably of rectangular construction, comprising a top member 4, side flanges 5, 6 and end flanges 7, 8.

A blotting element, such as ordinary blotting paper, is inserted between the flanges 7, 8, said blotting element comprising a longitudinally extending member 9, end

flanges 10, and ears 11 connected with the flanges 10. The flanges 10 are inserted between the end edges of a resilient pliant body 12 and the flanges 7, 8; and the ears 11 are inserted between the top member 4 and said resilient member as clearly shown in Figure 2. The resilient body 12 is preferably a sheet of sponge rubber and said member is of a length or width, or both length and width, that, when placed in position to hold the blotting element in the holder, it will be under compression longitudinally or transversely or longitudinally and transversely so as to firmly and releasably hold the flanges 10 of the blotting element in frictional engagement with the flanges 7, 8 of the holder. Owing to this no other fastening means are required to hold the blotting element in place in the holder and, therefore, the blotting element 9 may be quickly removed and a new one substituted therefor, by simply compressing the body 12 endwise or transversely and withdrawing it from the holder, removing the blotter 9 and placing a blotter of similar construction in position and then compressing the body 12 endwise or transversely and inserting it in the holder.

Now when the resilient body 12 is forced into the holder it will be subject to compression transversely and longitudinally, as well as in diagonal directions, and therefore it may be said that the resilient body, which is simply cut from a stock sheet and which is normally of constant thickness throughout, is placed under an inward radial compression. Thus the body tends to bulge outwardly at points adjacent its center. The tendency of the body to bulge in this way accomplishes three purposes, viz:—The body holds firmly in place against movement in any direction and against accidental dislodgment, the blotting element is held firmly in place, and the center of the blotting element will naturally be the first to contact with the surface against which it is pressed. It will be understood without the central bulge the edges of the resilient body would protrude slightly farther from the holder than would

the center. In fact it is well known that any material cut from sheet stock when pressed against a surface exerts more pressure adjacent the edges than at the center.

5. The bulge provided by the inward radial compression results in a void space being formed between the under surface of the top member of the holder and the top surface of the resilient body.

10. To prevent collapse of the body I propose to reinforce the body at central points and particularly fill up the void produced by the bulge. This may be done in various ways, but in the embodiment shown, I provide a single sheet 13 of relatively incompressible material, such as cardboard. Said sheet is hereinafter termed a filler pad. Said pad is of appreciably less area than the resilient body and is preferably glued 20 thereto.

It will be apparent now that when the device is applied to a surface to be blotted, the central portion of the blotting element will be first to contact. Slight pressure 25 will result in the resilient body adapting itself to the full area of the underlying surface to be blotted.

It will be apparent now that a simple sheet metal box, a blank of sheet rubber, 30 a blank of cardboard, and a blank of blotting paper are inexpensively cut and associated to provide a simple blotting pad which will effectively contact at all points throughout with a flat or irregular surface. 35 Other blotting pads require a rocking motion, whereas mine is applied directly and requires no rocking or tilting motion or other manipulation.

I am aware that it is not new to employ 40 sponge rubber above a blotting element, but in the prior known constructions the sponge rubber is not compressed into the holder so as to hold the blotting element in place as clearly set forth above.

45 It will be now clear that I have succeeded in producing a blotting pad of comparatively simple construction. Thus the blotting pad will be inexpensive to manufacture, can be sold at a profit for a comparatively small price, and a new blotter can be easily and quickly substituted for the old one.

I claim:

1. In a blotting pad, a rectangular rigid holder of box form open at the bottom and having side walls, end walls and a flat top wall, a flat sheet of resilient compressible material fitted in said box; the length, width and thickness respectively of said sheet of resilient material being normally greater than the length, width and depth respectively of the interior space of said holder, and a relatively incompressible filler pad coaxial with said resilient sheet and interposed between

the top surface thereof and the under surface of said top wall to hold portions of the sheet spaced therefrom; said filler pad being of reduced area as compared to said resilient sheet whereby the portions of said sheet adjacent its corners and edges are permitted to abut said top wall.

2. In a blotting pad, a rectangular rigid holder of box form open at the bottom and having side walls, end walls and a flat top wall, a flat sheet of resilient compressible material fitted in said box; the length of said sheet of resilient material being normally greater than the length of the interior space of said holder, and a relatively incompressible filler pad coaxial with said resilient sheet and interposed between the top surface thereof and the under surface of said top wall to hold portions of the sheet spaced therefrom; said filler pad being of reduced area as compared to said resilient sheet whereby the portions of said sheet adjacent its corners and edges are permitted to abut said top wall.

3. In a blotting pad, a rectangular rigid holder of box form open at the bottom and having side walls, end walls and a flat top wall, a flat sheet of resilient compressible material fitted in said box; the length, width and thickness respectively of said sheet of resilient material being normally greater than the length, width and depth respectively of the interior space of said holder, and a relatively incompressible filler pad coaxial with said resilient sheet and interposed between the top surface thereof and the under surface of said top wall to hold portions of the sheet spaced therefrom; said filler pad being of reduced area as compared to said resilient sheet whereby the portions of said sheet adjacent its corners and edges are permitted to abut said top wall.

4. In a blotting pad, a rectangular rigid holder of box form open at the bottom and having side walls, end walls and a flat top wall, a flat sheet of resilient compressible material fitted in said box; the length of said sheet of resilient material being normally greater than the length of the interior space of said holder, and a relatively incompressible filler pad coaxial with said resilient sheet and interposed between the top surface thereof and the under surface of said top wall to hold portions of the sheet spaced therefrom; said filler pad being of reduced area as compared to said resilient

sheet whereby the portions of said sheet adjacent its corners and edges are permitted to abut said top wall, a sheet of blotting paper extending over the exposed surface of said resilient sheet with its ends folded over respective ends of the resilient sheet and disposed between said resilient sheet and the under surface of said top wall; the thickness

of said blotting material being less than the thickness of said filler pad.

Signed at Los Angeles, California, this 10th day of May, 1922.

CHARLES S. YOUNG.
